Letters Patent No 1055. Dated Oct. 5. 1858.

The schedule referred to in these Letters Patent and making part of the same.

To all whom it may concern:

Be it Known that J. S. Vedder, of the City of Troy, in the County of Rensselaer, and State of New York, have invented or produced a new and original Design for Plates or Castings of a Cooking Stove, and I do hereby declare that the following is a full and exact description of the same, reference being had to the annexed photographic drawing, making a part of this Specification.

My ornamental design for each large door, A, of the oven consists of the dressed oval convex shield a, with its heraldic scroll-work border, B, arranged upon the central portion, and the ornaments c, in the corners, of its rectangular panel,

My ornamental design for the small doors, B, of the oven consists of the chased oval shield, d, with its carved border, e, occupying the central part, and the ornaments f, the angles, of its rectangular panel,

My design for the fire door or panel C, consists of the single large ornament thereon, composed of the embossed shield g, and its scroll work setting, h. - My design for each of the front-doors, D, consists of the central arrow marked shield i in its heraldic setting, j, arranged upon the oblong panel as shown. - My design for each foot, E, consists of the particular arrangement of scrolls, l, shown in the figure.

What I claim as my invention or production and desire to secure by letters patent is, the ornamental design of each door or panel A, B, C, D, and foot, E, of the cooking stove, as herein described and represented in the annexed photographic drawing.
